US00D779418S

(12) **United States Design Patent** (10) Patent No.: **US D779,418 S**
(45) Date of Patent: **** Feb. 21, 2017**

(54) **TIRE**

(71) Applicant: **SHANGDONG HONGSHENG RUBBER CO., LTD**, Shangdong Province (CN)

(72) Inventors: **Shuzhi Zhang**, Shandong Province (CN); **Yunxiang Qian**, Shandong Province (CN); **Feiyun Weng**, Shandong Province (CN)

(**) Term: **15 Years**

(21) Appl. No.: **29/543,488**

(22) Filed: **Oct. 26, 2015**

(30) **Foreign Application Priority Data**

Apr. 24, 2015 (CN) 2015 3 0114108

(51) LOC (10) Cl. **12-15**

(52) U.S. Cl.

USPC **D12/594**; D12/900

(58) **Field of Classification Search**

USPC D12/568-604, 900

CPC B60C 1/0016; B60C 11/0306; B60C 11/0302; B60C 3/06; B60C 9/17

See application file for complete search history.
